UNITED STATES PATENT OFFICE.

HARRY LANDSIEDEL, OF POPLAR BLUFF, MISSOURI, ASSIGNOR TO DALTON ADDING MACHINE COMPANY, OF ST. LOUIS, MISSOURI, A CORPORATION OF MISSOURI.

ADDING-MACHINE.

1,098,739.

Specification of Letters Patent. Patented June 2, 1914.

Application filed January 23, 1912. Serial No. 672,980.

To all whom it may concern:

Be it known that I, HARRY LANDSIEDEL, a citizen of the United States, residing at Poplar Bluff, in the county of Butler and State of Missouri, have invented new and useful Improvements in Adding-Machines, of which the following is a specification, enabling those skilled in the art to which my invention appertains to understand the same.

10 This invention relates to adding machines of the type in which there is a movable carriage arranged to receive a mechanical representation of the numbers to be added or recorded; and an object of the present invention is to provide a carriage for the purposes mentioned, of an improved and novel construction and of more facile operation than the carriages at present employed in adding machines.

20 Another object is to provide the carriage with a novel and superior escapement device and motor whereby the operation of the carriage is maintained securely within the limits of absolute and invariable accuracy, while 25 the speed of operation of the carriage may be suited to any requirements, and excess movement is positively avoided.

30 A further object is to provide the carriage with an escapement device in which the escapement racks are devoid of any direct spring connections, but are connected by a lever which insures alternate operation of the racks to permit movement of the carriage by the motor when the escapement 35 pawl or detent is moved from one to the other of said racks.

40 There are many other objects to be attained, all of which will be readily comprehended by those skilled in the art to which the invention relates, when the following description is read in the light of the accompanying drawings, in which—

45 Figure 1 is a side elevation showing the principal mechanism of a well-known adding machine in which my invention and improvements are embodied. Fig. 2 is a front side elevation of the carriage and associated mechanism, the key levers which operate to set up numbers in the carriage being in section. Fig. 3 is a view of the carriage from one end thereof, certain parts being in section on a line such as 3—3 of Fig. 2. Fig. 50 4 is a detail sectional view of the support for the escapement pawl or detent, the sec-

tion being on the line 4—4 of Fig. 3. Fig. 55 5 is a perspective view of the escapement-pawl support and universal bar. Fig. 6 is a plan view of the carriage and associated mechanism. Figs. 7 and 8 are detail views of the device connecting the escapement 60 racks. Figs. 9, 10, and 11 are detail sectional views on the line 9—9, 10—10 and 11—11, respectively, of Fig. 7.

The machine in which I have embodied my invention is known commercially as the 65 "Dalton" adding machine, and is constructed in substantial conformity with the adding department of the combined adding and writing machine disclosed in Hubert Hopkins's Patent No. 1,039,130, dated September 24, 1912, the application for which was filed January 24, 1903, Serial No. 140,390. In said machines there is a series of numeral keys and levers 1 which converge at their rear ends and are provided with a row of 75 hammers 2. The keys on these levers are in transverse rows at the front of the machine, and the hammers 2 are in a longitudinal row which is transverse to the rows of keys. Said machines have transverse rails 3 on 80 which a carriage operates. Said carriage is supported by anti-friction rollers 4 which operate upon the rails 3. Series of rows of pins 5 are mounted in the carriage and are settable by the key-levers 1 and hammers 2 85 to represent numbers. A number of type-carriers 6 and a number of racks 7 swing from a shaft 8, and are operated forwardly and rearwardly through suitable mechanism and appliances controlled by a main shaft 9, 90 a handle 10, or other means being used for operating said shaft. Such operation of the type-carriers and racks, irrespective of the devices for effecting their operation, results in a record of the numbers represented in 95 the carriage being produced on paper on a platen 11, and also results in operation of the adding mechanism 12 effectively to add said numbers.

My present invention relates to the carriage and to its associated mechanism and to the mechanism for operating and controlling the carriage.

My invention includes improvements in the arrangement and construction of the 100 rails 3. In previous machines these rails are separate or detached parts, mounted on separate supports. Obvious infirmities are in-

herent in such construction and arrangement, among which may be mentioned the insecurity of adjustment and the liability of becoming flexed or bent, thereby destroying the accuracy of the machine when used for adding and recording numbers. I provide an integral casting in which the rails 3 are component parts. In said casting there are three bridges or arches 3^a connecting the side posts 3^b, of which there are three at the front side and three at the rear side of said casting. The rail 3 at the rear is integral with upward extensions of said arches and posts, and the single roller 4 which supports the rear side of the carriage, operates upon said rail 3. The rail 3 at the front side of the casting is integral with E-shaped brackets or extensions of the arches and posts, the upper surface of said front rail being in the same horizontal plane with the first-named rail. On the front side of the carriage there are two rollers 4 which operate upon the upper surface of the front rail. It will be noted that the three anti-friction rollers constitute a tri-cycle support for the carriage, insuring absolute and accurate balance of the carriage upon the firm and unchangeable support and track, at all times and under all conditions. The integral support cannot become flexed, nor any parts thereof dislocated. In its idle or normal position the carriage is at the right hand side of the machine with respect to the operator. At the opposite side of the machine is a vertical rock shaft 13 to which is attached an arm 14. A spring 15 has one end connected to said arm and the opposite end connected to a stationary part 16, whereby said shaft 13 is actuated in one direction. An arm or lever 17 is attached to the shaft 13 and is provided in its opposite or front end with an elongated slot 18 which receives a pin 19 on the carriage, so that the spring 15 constitutes a motor for moving the carriage from right to left in the machine, or from lower to higher orders, as the numeral keys are operated. The movement from right to left, that is from lower to higher orders, is effected step by step through the medium of an escapement device controlled by the key levers 1.

The rock shaft 20 extends transversely under the key-levers 1 and is supported by adjustable point bearings 21 carried by the parts 3^b at the sides of the machine. Two arms 22 are attached to the rock shaft 20, and said arms support the universal bar 23 which rests and is held yieldingly upon the upper edges of the key-levers 1 by a suitable spring 24. Operation of any of the key-levers 1 raises the universal bar 23 and rocks the shaft 20. An arm 25 rigid with the shaft 20 has a pin 26 projecting through a slot in a plate 27 rigid with the machine base, thereby limiting the movement of the

parts and preventing disarrangement thereof. A pawl support 28 is mounted on the shaft 20 and has a hole in its lower end into which the pin 26 extends. Set screws 29 are operatively mounted in the part 28 and are adjustable to bind against the pin 26 and hold the support 28 in exactly the required position. A pawl 30 is mounted in a housing on the support 28 above the shaft 20, and is actuated upwardly by a spring 31 (Fig. 4). A pin 32 attached to a pawl extends into a slot in the housing and thereby limits movement and prevents dislodgment of the pawl.

The carriage has two depending arms 33 which extend below the front rail 3 and which carry studs 34. Two racks 35 are under the front rail 3, have slots (Figs. 7 and 8) through which the studs 34 extend and thereby support said racks and permit them to move or to be moved in the direction of their length, which is transversely over the key-levers 1. Said racks are separated by washers 36. One of said racks 35 has a slot 37 (Figs. 7 and 8) through which extends the pivot 38 of a pivoted toggle-coupling or coupling-lever 39, said pivot 38 being supported by one of the arms 33. One of the racks 35 has a notch in its upper edge, and the other of said racks has a similar notch in its lower edge which receive pins 40 on the ends of the lever 39. In idle position the pawl 30 is in engagement with the rack 35 which is in front (Fig. 3), but when any of the numeral key-levers 1 are operated and the shaft 20 is rocked, said pawl 30 is moved into engagement with the other rack 35. This permits the motor spring 15 to move the carriage the distance of one-half of one step or space. When the key-lever 1 is released the spring 24 rocks the shaft 20 to its idle or normal position, thereby moving the pawl 30 into engagement with the front or first rack 35 and permitting the motor spring 25 to move the carriage the remaining half step or space. The coupling-lever 39 maintains the racks in accurate adjustment and prevents excess movement of either one. It will be noted that the escapement racks are devoid of spring connections and that they are actuated only by the motor spring 15 in the step by step movement of the carriage. One side of the pawl 30 is beveled or cut obliquely so that as the carriage is moved toward its idle position or starting point the rack teeth will slide over said pawl and press it downwardly into the housing in opposition to the pawl-actuating spring 31. The means for moving or restoring the carriage to its position or starting point includes an arm 41 (Figs. 2 and 6) pivoted to the rock shaft 13 and having a pin 42 which is arranged to engage with a pin 43 on the arm 14 when the said arm 41 is swung rearwardly, and

thereby turn the shaft 13 effectively to force the carriage toward the starting point. A link 44 has its rear end pivoted to the arm 41 and constitutes a mechanical element in the machine for operating the shaft 13 to restore the carriage to its idle position or starting point after each operation.

From the foregoing it will be clear that the carriage control mechanism is accurate and positive in its movements, and is devoid of delicate and fragile elements which, in such devices, are the subject of many objections and infirmities.

It is apparent that many modifications will suggest themselves to those skilled in the art to which the invention relates without departure from the spirit and scope of the invention. I do not restrict myself to identical features of construction or arrangement, but

What I claim and desire to secure by Letters-Patent is—

1. The combination of a support adapted to be moved, keys, levers connected with and operated by said keys, two racks carried by and movable with respect to said support, a universal bar moved by said levers at each operation thereof, a pawl, a spring normally holding said pawl in engagement with one of said racks, means actuated by said universal bar for moving said pawl into engagement with the other one of said racks when any one of said levers is operated, means for moving said support when said pawl is operated as aforesaid, substantially as specified.

2. The combination of a support, keys, levers connected with and operated by said keys, two racks movably carried by said support, a pawl, means for moving said pawl into engagement with said racks alternately when any one of said levers is operated, a coupling pivotally connecting said racks and acting to move the other rack when said support is moved relative to either of said racks, and a spring for moving said support, substantially as specified.

3. The combination with a support, of two racks slidably carried by said support, a pawl normally in engagement with one of said racks and holding said support from movement, means for moving said pawl into engagement first with one and then the other of said racks to permit a single step movement of said support, means for moving said support when the said pawl is so moved, and a device actuated incidentally to movement of said support to move each of said racks relative to said support, substantially as specified.

4. The combination with a support adapted to be moved and a spring for moving said support, of two racks supported by said support, a coupling-lever pivotally connecting said two racks for moving each rack rela-

tive to the other, a pawl engaging one of said racks to hold said support from movement, means for moving said pawl into engagement with the other of said racks and then again with the first-named one of said racks at each step movement of said support, and a spring for moving said support one step when said pawl is operated as aforesaid, substantially as specified.

5. The combination with a support adapted to be moved, a shaft, a connection from said shaft to said support, and a spring rotating said shaft to move said support, of two racks slidably mounted by said support, a pawl arranged to engage one of said racks to prevent movement of said support, levers for moving said pawl into engagement with the second one of said racks, a spring for moving said pawl again into engagement with the first one of said racks and a coupling device for actuating each of said racks relative to the other, substantially as specified.

6. The combination with a movable support, a series of levers, and a motor for moving said support, of stepping means for said support comprising two racks supported by said support, a coupling-lever-connecting said racks whereby said racks will be moved in opposite directions, and a pawl controlled by said first-named levers to engage said racks alternately and permit said motor to move said support, substantially as specified.

7. The combination of a support adapted to be moved step by step, levers, a motor spring for moving said support, a rack slidably carried by said support, a pawl engaging said rack and holding said support from movement, a second rack slidably carried by said support, a coupling-lever pivotally connecting said two racks, the combined movement of said two racks equaling a step or space in the movement of said support, and means moving said pawl out of engagement with said first-named rack into engagement with said second-named rack, and then back into engagement with said first-named rack, incidentally to the operation of each of said first-named levers to permit movement of said support, substantially as specified.

8. The combination with a support adapted to be moved step by step, levers, a motor spring for moving said support, a rack slidably carried by said support, a pawl engaging said rack and holding said support from movement, a second rack slidably carried by said support, a coupling-lever pivotally connecting said two racks, the combined movement of said two racks equaling a step or space in the movement of said support, and means moving said pawl out of engagement with said first-named rack into engagement with said second-named

rack, and then back into engagement with said first-named rack incidentally to the operation of each of said first-named levers to permit movement of said support; and means for restoring said support to its starting point while said pawl is in contact with said first-named rack, substantially as specified.

9. The combination with a movable support adapted to be moved step by step, and means for moving said support, of two racks mounted on and movable with respect to said movable support, a pawl, means for moving the pawl into engagement with said racks alternately, and a lever pivotally uniting said racks whereby one of said racks will be moved with respect to the other rack which is in engagement with said pawl, incidentally to the movement of said support.

10. The combination with a movable support adapted to be moved step by step, and means for moving said support, of two racks carried by and movable with respect to said support, a lever pivotally uniting said two racks whereby movement of one of said racks will actuate the other of said racks, and a pawl operative to engage with said racks alternately.

11. In a machine of the character described, a support, levers, two racks carried by said support, a shaft, a pawl supported by said shaft, a spring normally holding said pawl in engagement with one of said racks, a universal bar operated by said levers for moving said pawl into engagement with the other one of said racks when any of said levers is operated, a device controlled by said support and by each of said racks for moving both of said racks relative to said support incidentally to movement of said support, and connections for moving said support, substantially as specified.

12. In a machine of the character described, a movable support, levers, two racks carried by said support, a pawl, a shaft for moving said pawl into engagement with said racks alternately when any one of said levers is operated, means actuated by said levers for moving said pawl, a coupling pivotally connecting said racks, whereby when one of said racks is held by said pawl the other rack will be actuated incidentally to movement of said support, and a spring actuated lever for moving said support, substantially as specified.

13. In a machine of the character described, the combination with a movable support, of two relatively movable racks carried by said support, a pawl normally in engagement with one of said racks and holding said support from movement, a rock shaft supporting said pawl, means for rocking said shaft to move said pawl into engagement, first with one and then with

the other of said racks to permit step by step movement of said support, a coupling controlled by said racks for actuating said racks in opposite directions incidentally to the aforesaid operation of said pawl, and a spring for moving said support when said pawl is so moved, substantially as specified.

14. The combination with a movable support, of a spring for moving said support, two racks supported by said support, a coupling-lever pivotally connecting said two racks, a pawl engaging one of said racks to hold said support from movement, a rock shaft supporting said pawl, means for moving said pawl into engagement with the other of said racks and then again with the first-named one of said racks at each movement of said pawl, and a spring actuated lever connected to said support for moving said support when said pawl is operated, substantially as specified.

15. The combination with a movable support, a shaft, a connection from said shaft to said support, and a spring rotating said shaft to move said support, of two racks slidably carried by said support, a rock shaft, a pawl supported by said rock shaft and arranged to engage one of said racks to prevent movement of said support, a universal bar operable to rock said shaft in one direction to engage said pawl with the second one of said racks, a pivoted coupling, for controlling the movement of said racks, levers for actuating said universal bar, and a spring for moving said pawl again into engagement with the first one of said racks, substantially as specified.

16. The combination of a movable support, levers, and a motor for moving said support, stepping means for said support comprising two racks supported by said support, a coupling-lever connecting said racks whereby said racks will be moved in opposite directions, a rock shaft, a pawl carried by said rock shaft, a universal bar actuated by said first-named levers for moving said pawl into engagement with one of said racks, and a spring for moving said pawl into engagement with the other of said racks, substantially as specified.

17. The combination of a movable support, a motor for moving said support, two racks carried by and movable relative to said support, a rock shaft, a pawl supported by said rock shaft, a spring actuating said rock shaft to hold said pawl in engagement with one of said racks, arms carried by said rock shaft, a universal bar carried by said arms, levers operable to move said universal bar to move said pawl into engagement with the other one of said racks, and means preventing excess movement of said rock shaft, substantially as specified.

18. The combination with a support, two

5 racks carried by and movable with respect to said support, a lever pivoted upon said support, a connection between said lever and each of said racks, a pawl, means for moving said pawl alternately into engagement with said racks, and means for moving said support when said pawl is operated as aforesaid.

19. The combination with a carriage to be moved, and a motor for moving said carriage, of a plurality of studs supported by said carriage, two racks slidably mounted on said studs, a lever engaging both of said racks whereby when one of said racks is moved in one direction the other rack will be moved in the opposite direction, an escapement pawl, and means for engaging said pawl alternately with said racks to enable said motor to move said carriage.

20. 20. The combination with a carriage to be moved, and a motor for moving said carriage, of two racks supported movably by said carriage, a device engaging one of said racks for controlling the movement of said carriage, means for shifting said device to engage said racks alternately, and means whereby the power of said motor will move said racks relatively to effect step by step movement of said carriage, substantially as specified.

21. The combination with a carriage to be moved, and a motor for moving said carriage, of two racks movably supported by said carriage, a lever pivotally connecting said racks whereby movement of one rack in one direction actuates the other rack in the opposite direction, and an escapement pawl arranged to engage with said racks alternately, substantially as described.

22. The combination with a carriage to be moved, and a motor for moving said carriage, of two racks supported by and movable with respect to said carriage, an escapement pawl, means for engaging said escapement pawl with said racks alternately, and a lever supported by said carriage and

engaging both of said racks, substantially as specified.

23. The combination with a carriage to be moved, and a motor for moving said carriage, of two racks slidably carried by said carriage, a pawl normally in engagement with one of said racks and holding said carriage from movement, and means for moving said pawl into engagement first with one and then the other of said racks to permit a single step movement of said carriage.

24. The combination with a carriage to be moved, and an actuator for moving said carriage, of two racks movable with respect to said carriage and controlling movement of said carriage, a pawl arranged to engage one of said racks to prevent movement of said carriage, levers for moving said pawl into engagement with the second one of said racks, a spring for moving said pawl again into engagement with the first one of said racks, and a lever supported by said carriage for actuating each of said racks relative to the other, substantially as specified.

25. The combination with a carriage to be moved, and a motor for moving said carriage, of two racks supported by said carriage, a pawl normally engaging one of said racks to prevent movement of said carriage, levers for moving said pawl into engagement with the second one of said racks, a spring for moving said pawl again into engagement with the first one of said racks, and means for actuating each of said racks relative to the other, substantially as specified.

In testimony whereof, I have signed my name to this specification in the presence of two subscribing witnesses.
